UNITED STATES PATENT OFFICE.

GEORGE W. RAY, OF FORTY FORT, PENNSYLVANIA.

AEROPLANE.

Application filed March 9, 1927. Serial No. 173,944.

The present invention relates to an aeroplane of the gyroscope type and has for its principal object to provide a plane of this nature which is easy to manoeuvre for the purpose of ascending and descending in a vertical line or at an incline, as may be desired.

Another very important object of the invention lies in the provision of an aeroplane of this nature that may be easily and conveniently controlled.

Another very important object of the invention lies in the provision of an aeroplane of this nature which is comparatively safe since it can be regulated to function as a parachute for descending purposes.

A still further very important object of the invention lies in the provision of an aeroplane of this nature that is exceedingly simple in its construction, comparatively inexpensive to manufacture, strong and durable, thoroughly efficient and reliable in operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a sectional side elevation of the aeroplane embodying the features of my invention,

Figure 2 is a sectional front elevation thereof,

Figure 3 is a top plan view thereof,

Figure 4 is a detail section through the gyroscopic lifting member.

Referring to the drawings in detail it will be seen that the numeral 5 denotes four bars which radiate from a disk 6' and are connected with depending bars 6 by brace brackets 7 and being further braced in respect thereto by guy wires 8. Two of the opposed bars 6 are connected intermediate their ends by a cross bar 9 extending transversely of the aeroplane being held in place by brace brackets 10 or in any other suitable manner. A shaft 11 is journaled in the disk 6' and in the bar 9. A hub 12 is provided on the shaft 11 and has radiating therefrom fixed blades 14 connected at their outer ends to an annular rim 15. A pair of hub members 16 are fixed to the shaft 11 one adjacent

disk 6' and another adjacent rod 9. A plurality of guy wires extend from the hub members 16 to the annular rim 15 as is indicated at 7. As is shown to advantage in Figures 1 and 4, a leaf 18 is hingedly mounted as at 19 to each blade 14 on the upper edge thereof. These leaves 18 are limited in their movement between the lower edges of the next adjacent blades as is shown in Figure 1 or to the position underlapping their respective blades as in Figure 4. Guy wires 20 connect the ends of the respective bars 5 as is clearly shown in Figure 3. Braces 21 extend downwardly from points a slight distance from the center of the rod 9 to the lower ends of the rods 6. A pair of hangers 22 is disposed to one side of the center of the rod 9 adjacent the juncture therewith of the braces 21. Links 23 are swingably engaged with these hangers 22 and support a housing 24 which may swing in a longitudinal plane with the aeroplane. Guy wires 25 are engaged with the bottom of the housing 24 and are engaged with the side bars 6 adjacent the brackets 10 thereon.

Stabilizing vanes 28 and 29 extend downwardly and incline outwardly in opposite directions from the longitudinal cross member 9 as is indicated to advantage in Figure 2 and are braced by members 30 in respect to braces 21. A pair of engines 31 are mounted in the casing or housing 24 and have their crank shafts in alinement and are geared as at 32 with a vertically rising shaft 33 that is connected with shaft 11 by a universal coupling 34. A rudder 35 is hingedly mounted on the rear bar 6 and is operable by a link 36 and a lever 37. A link 38 is attached to the front bar 6 and to a lever 39 preferably located within the housing 24 so that the housing 24 may be swung to dispose the shaft 33 at an angle to the shaft 11 so that the aeroplane may ascend or descend at an incline and also for the purpose of making progress forwardly and rearwardly.

Buffer elements 40 extend downwardly and outwardly from the bottom of the housing 24 and similar buffer elements 41 extend downwardly and outwardly from the lower ends of the bars 6. The lower ends of the bars 6 are connected by guy wires 42.

From the above detailed description it will be seen that I have devised an aeroplane structure which is strong and durable because of the bracing between the various

parts thereof. This aeroplane consists of comparatively few parts all of which are rather inexpensive to manufacture so that the whole may be manufactured at a reasonably low cost. The control of the aeroplane is very simple and almost obvious. When the shafts 11 and 33 are alined and the plates 14 are in operation, it will be seen that the leaves 18 will automatically take the position shown in Figure 4 and the aeroplane will rise straight up and the wings 28 and 29 will resist the torque or twist. If it is desired to go forwardly or rearwardly this may be accomplished by swinging the lever 39 to tilt the housing rearwardly or forwardly respectively. If the power plant should become out of order the plane will descend slowly because the blades will function as a parachute and these will take the position shown in Figure 1 to prevent air from rushing between the blades.

As a further precaution against the machine rotating about its vertical axis, a shaft 50 is rotatable in brackets 51. The lower hub member 16 has a gear 16' formed thereon and meshing with a pinion 52 on the shaft 50. A shaft 53 is journaled in a bracket 54. Gearing 55 operatively connects the shaft 50 and 55. A propeller 56 is fixed 30 on the shaft 53 and when rotated tends to overcome any twisting tendency.

It is thought that the construction, operation, and advantages of this invention will

now be quite apparent to those skilled in this art without a more detailed description thereof. The present embodiment of the invention has been disclosed in detail merely by way of example since in actual practice it attains the features of advantage enumerated as desirable in the statement and the above description. It will be apparent that numerous changes in the details of construction, and in the combination and arrangement of parts may be resorted to without departing from the spirit or scope of the invention as hereinafter claimed or sacrificing any of their advantages.

Having thus described my invention, what I claim as new is:—

In an aeroplane, a power plant, means for suspending the power plant from the aeroplane in the manner of a pendulum, a gyroscopic member rotatable in the aeroplane, a drive shaft from the power plant operatively connected with the gyroscopic member, means for limiting the swinging of the power plant in a single plane, means for swinging the power plant for guiding the ascent and descent of the aeroplane, means for guiding the aeroplane, wings supported by the aeroplane longitudinally thereof and inclined outwardly in opposite directions to counteract the torque of the aeroplane.

In testimony whereof I affix my signature.

GEORGE W. RAY.
